(57) **CLAIM**

The ornamental design for a coupling for endoscope fiber and light source, as shown and described.

DESCRIPTION

FIG. 1 is a top front perspective view, showing the coupling for endoscope fiber and light source in an environment of use;

FIG. 2 is a top front perspective view thereof;

FIG. 3 is a bottom rear perspective view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front elevational view thereof; and,

FIG. 9 is a rear elevational view thereof.

The broken lines in FIG. 1 depicting plates and a rod illustrate environmental subject matter that form no part of the claimed design. The remaining broken lines depict portions of the coupling for endoscope fiber and light source and form no part of the claimed design. The long dash short dash broken lines in FIG. 1 illustrate guide lines.

1 Claim, 2 Drawing Sheets
